UNITED STATES PATENT OFFICE.

WILLIAM McILROY, OF ROCHESTER, NEW YORK.

BASE-BALL-GAME APPARATUS.

1,122,141.

Specification of Letters Patent. Patented Dec. 22, 1914.

Application filed February 11, 1914. Serial No. 818,102.

To all whom it may concern:

Be it known that I, WILLIAM McILROY, a citizen of the United States, residing at Rochester, in the county of Monroe and 5 State of New York, have invented certain new and useful Improvements in Base-Ball-Game Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

This invention relates to new and useful improvements in baseball game apparatus and the object in view is to produce a simple and efficient apparatus of this nature so 15 arranged that the various plays in a game of ball may be reproduced.

My invention is illustrated in the accompanying drawings, in which:—

Figure 1 is a top plan view of the apparatus. Fig. 2 is a sectional view on line 2—2 of Fig. 1. Fig. 3 is a section on line 3—3 of Fig. 2. Fig. 4 is a sectional view transversely through one corner of the frame of the apparatus. Fig. 5 is a detailed perspective view of a closure for the reception of the ball, and Fig. 6 is a view of one of the men which are utilized for designating different locations where the players are positioned.

Reference now being had to the details of the drawings by letter, A designates a board which has a circumferential flange A' to prevent the ball from rolling off the board and at the lower corner of the board is a slot B in which a plate C is fastened by screws C' and which plate carries a pivotal pin C' upon which a bar D is pivotally mounted, one end D' of which bar has its ends bent at right angles and apertured for 35 the reception of the longitudinal shaft E, which latter has a scoop-shaped end E' for the reception of the ball F. A coiled spring H is mounted intermediate the outer end of said angle bar and a washer I which is held 40 by means of a pin I'. A buffer spring K is mounted between the head E² of said shaft and the adjacent angled end D' of said bar D. A rod O is fastened to the under surface of said bar D and has a concaved end O' for the reception of the thumb of the

operator, as shown in Fig. 1 of the drawings.

A movable trigger, designated by letter Q, has apertured flanges Q' through which the rod O passes, said trigger having also an integral hook Q² for engagement over the head E² of the shaft E when it is desired to pull the shaft back to put the spring H under tension. Said trigger has a laterally extending hook Q³ over which one end of the coiled spring Q⁴ passes and which spring has its free end bridging the space Q⁵ formed in the plate forming the trigger, said spring Q⁴ being provided for the purpose of holding the index finger of the hand in 70 said space, as shown in Fig. 1.

The several bases are designated in the drawings, the home plate by numeral 4, first base by numeral 1, second base by numeral 2, third base by numeral 3, and inclosures, 75 designated respectively by letters J, are positioned at various locations about the field and the bottom of each of said inclosures, one of which is shown in enlarged detail in Fig. 5, is provided with upset portions J', 80 inclined upon their outer edges and provided for the purpose of allowing the ball to roll into the inclosure but preventing the same from rolling out again. At the diametrically opposite corner of the board from the one in which the shaft E is mounted is a similar spring-pressed shaft, designated by letter S, with a head S' at one end and said shaft is mounted upon a bar S² pivotally mounted upon a pivotal pin S³ and said bar S² has an oscillating movement in a recess formed in the corner of the board, while the head thereof is adapted to have a range intermediate the vertical partitions T which extend out at right angles from the sides of 85 the board. The home plate 4 is positioned midway between the ends of said partition.

The various men are designated by letter V.

In playing the game, the batter is supposed to place the ball upon the scoop-shaped end E' and, by catching the hook part up over the head of the shaft and pulling back upon the same, the spring H will be put under tension. A lateral swinging 100 movement to the trigger will release the shaft and the ball may be fired toward the opening between the partitions T. It is the purpose of the batter, who operates the spring-pressed shaft with the head S' in 105 110

the diagonally opposite end of the board, to strike the ball with the head S' and, by so doing, cause the same to rebound and pass over one or the other of the lines L, L' or L². In the event of the ball stopping in the space intermediate the home plate and the line L, the player makes one base and one of the figures representing a man is placed upon first base. If the ball stops 10 intermediate the lines L and L', it represents a two base hit and, should the ball stop intermediate the line L and L², a man is placed upon third base and, if the ball stops in the corner at the extreme lower end of the board, it designates a home run. In the event of the person operating the spring-pressed plunger representing the batter firing the ball into one of the inclosures, it counts for an out. If the ball fired by 15 the operator representing the pitcher at the lower end of the board strikes the head S' and is not returned into either of the spaces counting for a run, a foul is counted and, if the ball passes into the space intermediate 20 the partitions T without coming in contact with the head S', a strike is recorded and, if the ball fails to come within the space intermediate the partitions T, a ball is counted. The game is played in the same manner 25 as the actual game of ball, three strikes being out and a base being taken on four balls.

What I claim to be new is:—

1. A baseball game apparatus comprising, in combination with a board, swiveled 30 members mounted at the diagonally opposite corners thereof, spring-pressed shafts carried by said members, a ball holder upon one of the shafts, and means for releasing 35 the ball carrying shaft.

2. A baseball game apparatus comprising, in combination with a board, swiveled members mounted at diagonally opposite 40 corners thereof, spring-pressed shafts carried by said members and each shaft pro-

vided with a head, a buffer spring intermediate each head and the member on which the shaft is mounted, a ball carrying receptacle at the end of one shaft, and means for drawing the shaft back and releasing the same. 45

3. A baseball game apparatus comprising, in combination with a board, swiveled members mounted at diagonally opposite corners thereof, spring-pressed shafts carried by said members and each shaft provided with a head, a buffer spring intermediate each head and the member on which the shaft is mounted, a ball carrying receptacle at the end of one shaft, an extension rod upon one member, a member having laterally projecting lugs which are apertured and adapted to move upon said extension, a hook upon said lug member for engagement with the head of said shaft, and a concaved end to said extension. 55

4. A baseball game apparatus comprising, in combination with a board, swiveled members mounted at diagonally opposite corners thereof, spring-pressed shafts carried by said members and each shaft provided with a head, a buffer spring intermediate each head and the member on which the shaft is mounted, a ball carrying receptacle at the end of one shaft, an extension rod upon one member, a member having laterally projecting lugs which are apertured and adapted to move upon said extension, a laterally projecting hook portion upon the member with the lug thereon, and a coiled spring engaging said laterally projecting hook and designed to hold a finger against the edge of the lug member. 60

In testimony whereof I hereunto affix my signature in presence of two witnesses.

WILLIAM McILROY.
